TOY TRACKWAY FOR TRAIN

Yukio Sugihara, Tokyo, Japan, assignor to
Toytown Corporation, Tokyo, Japan

Filed May 27, 1975, Ser. No. 580,742

Term of patent 14 years

Int. Cl. D21—01

U.S. Cl. D34—15 MM

FIG. 1

FIG. 1 is a top plan view of a toy trackway for train, embodying my new design;

FIG. 2 is a front elevational view thereof;

FIG. 3 is a right side elevational view thereof; and

FIG. 4 is a left side elevational view thereof.

The bottom plan view is plain and unornamented and the rear elevational view of the station member is plain and unornamented.

I claim:

The ornamental design for a toy trackway for train, as shown and described.
